UNITED STATES PATENT OFFICE.

FRANK LAVAN, OF GORHAM, COLORADO.

COMBINED KITCHEN CABINET AND SINK.

1,296,670.

Specification of Letters Patent. Patented Mar. 11, 1919.

Application filed April 4, 1916. Serial No. 88,791.

To all whom it may concern:

Be it known that I, FRANK LAVAN, a citizen of the United States, residing at Gorham, county of Boulder and State of Colorado, have invented certain new and useful Improvements in Combined Kitchen Cabinets and Sinks; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in a combined kitchen cabinet and sink, my object being to provide a convenient, durable and economical device of this character which shall be more particularly adapted for use in the country or in localities where pressure water systems are not available.

In my improved construction the cabinet feature includes a tank adapted to be filled with water at intervals; a sink and a tank below the sink, the sink forming a closure for the upper extremity of the tank and being adapted to discharge into the latter, whereby the water which is caught in the lower tank may be employed for other purposes even though soiled to some extent. In localities where water is not plentiful this is an important feature, and the water for instance, which is used in the sink for washing dishes and for other purposes, may be discharged into the tank below, and may be drawn off therefrom and used for such purposes as it may be available. Another feature of my improvement consists in a hinged drain board which may be detachably connected with either extremity of the sink, the same being locked in place after the sink is assembled in coöperative relation with the tank.

Having briefly outlined my improvement, I will proceed to describe the same in detail, reference being made to the accompanying drawing, in which is illustrated an embodiment thereof. In this drawing,—

Figure 1 is a section taken approximately on the line 1—1, Fig. 2.

Fig. 2 is a vertical section taken approximately on the line 2—2, Fig. 1, looking toward the right.

Fig. 3 is a detail view of the cabinet member of the structure, shown detached from the sink member.

Fig. 4 is a detail view of the sink member looking in the direction of arrow 4.

Fig. 5 is a detail view of the drain board. 60

Fig. 6 is a fragmentary top plan view of one corner of the sink.

The same reference characters indicate the same parts in all the views.

Let the numeral 5 designate a sink having beveled side walls adapted to enter the beveled top portion 6 of an upright tank 7. A flange 8 extends around the ends and front of the sink, and the edges of this flange are downwardly and inwardly curved 70 as shown at 9, a hook shaped member 10 thus being formed at each end adapted to receive a rod 12 which is secured to the adjacent portion 13 of a drain board or member 14. This rod is spaced from the 75 bottom of the drain board by short members 15, so that before the sink is placed upon the tank, the rod 12 may be made to enter either hook-shaped member 10, the parts 15 entering vertical slots 16 formed 80 in the end portions of the inner hook-shaped edge of the sink, the drain board being supported in the assembled relation by means of a chain 17 which is connected at one extremity with an eyebolt 18 in the 85 drain board and at its opposite extremity with a hook or staple 19 attached to one side of the upright cabinet 20 which rests upon the rear horizontal flange 21 of the sink. 90

After the drain board has been connected with the sink as just explained, the latter may be set into the tank 7, after which the draining board is locked in place, since it cannot be moved far enough inwardly to 95 disconnect it from the hook-shaped member 10. When the chain 17 is unhooked from the device 19, the board may be swung downwardly to occupy a vertical position, this movement being permitted by virtue 100 of the slots 16 formed in the hook-shaped member 17 of the sink.

The sink contains a central opening 22 formed in a part 23 which is depressed to form a recess 24 which is adapted to receive the exteriorly projecting flange 25 of a depending sleeve or nozzle 26. The joint between the two flanges is filled with a packing material 27 in order to form a fluid-tight joint, when the valve or stopper 28 is in place. The member 26 is held in place by means of a closure 29 having an upwardly projecting threaded flange 30 which is screwed upon the exteriorly

threaded lower portion of the nozzle 26. The part 29 is perforated as shown at 31 to allow the water to pass from the sink into the tank 7 below, when the plug or valve 5 28 is removed. The perforated portion of the device 29 forms a strainer, whereby any solid material which may be in the sink, is strained out of the water which is discharged into the tank. This tank contains 10 an opening 32 near its bottom which is normally closed by a screw plug 33. The tank is also equipped with a draw-off cock or faucet 34 which is also located as nearly at the bottom of the tank as practicable 15 for obvious purposes.

The tank is provided with a metal lining 35 as is customary with receptacles whose body portions are composed of wood and which are adapted to hold liquid.

20 The cabinet 20 is connected with the rear flange 21 of the sink, by means of two hook-shaped pins 36 which are caused to enter openings 37 formed in the flange 21. It will be understood that the cabinet is connected 25 with the flange of the sink when the apparatus is moved sufficiently away from the wall 38 for the purpose. The cabinet is then held in a horizontal position and after inserting the free extremities of the hooks 36 in the 30 openings 37, the cabinet is raised to the upright position and during this operation the hook-shaped pins 36 assume the position shown in Fig. 2. Then, as the structure is moved into its proper relative position, 35 whereby the back of the cabinet engages the wall 38, the structure will be held securely in place. The bottom of the cabinet is also provided with forwardly located straight pins 48 adapted to enter recesses 49 in the flange 44, when the cabinet is in the upright position. The straight pins 48 coöperate with the hook-shaped pins 36 to maintain the cabinet member in place.

The cabinet 20 contains a water tank 39 45 which is metal-lined as shown at 40 and equipped with a draw-off cock or faucet 41, the latter being arranged in front and in such a position that as the valve of the faucet is opened, the water will enter the sink. The 50 cabinet is further provided with end members 42 and 43 having hinged doors 44 and 45. Furthermore, the upper extremity of the water receptacle 39, is equipped with outwardly projecting ears 46 with which a mirror 47 may be pivotally connected, whereby the mirror may occupy a forwardly inclined 55 position (see Fig. 2).

From the foregoing description the use and operation of my improved structure will be 60 readily understood and need not be described further in detail. As shown in the drawing, my improvement is so constructed that the

drain board may be located at either extremity of the sink.

It should be explained that in connecting 65 the drain board with the hook-shaped flange 10 at either end of the sink, the connection is made before the sink is in place in the tank, and in this event the drain board is held in the inverted position, approximately as indicated by broken lines in Fig. 1. When in this position or when held at this inclination 70 it will be seen that the rod 12 may be moved into position within the groove of the flange, by virtue of the fact that the parts or arms 75 15 of the U-shaped rod, enter the slots 16 of this flange. As soon as the rod is in position, assuming that the drain board is arranged as indicated by the broken lines or at an angle of about 45 degrees, the drain board 80 may then be swung toward the right or in the direction of arrow 5 (see Fig. 1), until it occupies the full line position in Fig. 1, the parts 15 of the rod moving in the slots 16 as will be readily understood. After this is 85 done the chain 17 is connected with the part 19 of the cabinet, whereby the drain board is supported in operative relation with the sink or in position for use. It will be understood 90 that the chain extends rearwardly from the drain board, since the cabinet is located in the rear of the position of the drain board. This arrangement removes the chain from interference with the use of the drain board in the regular way. If the chain extended in 95 the longitudinal direction of the drain board, it is evident that it might interfere more or less with the use of the board, but by virtue of the fact that it is carried rearwardly in the direction of the wall 38 in order that it 100 may be connected with the cabinet, this difficulty is overcome.

When the drain board is not in use the chain 17 may be disconnected from the cabinet, after which the board is allowed to drop 105 downwardly to the vertical position indicated by dotted lines in Fig. 1.

Having thus described my invention, what I claim is,—

The combination of a sink, a tank forming 110 a support for the sink and having communication therewith by a valve-controlled opening in the sink, the latter having a horizontal rearwardly extending flange, a cabinet detachably connected with the said flange 115 through the medium of hook-shaped and straight pins adapted to enter recesses formed in the sink flange for the purpose.

In testimony whereof I affix my signature, in presence of two witnesses.

FRANK LAVAN.
